CARL A. BRANDT, OF GREAT NECK, NEW YORK.

WATER SCREEN.

Application filed October 24, 1925. Serial No. 64,623.

My invention relates to steam boilers and has particular reference to the construction of water screens for lining the furnace and combustion chamber walls as a protection against excessive temperatures and for increasing the evaporative capacity and efficiency of the boiler.

The use in modern boiler plants of fuel oil and pulverized coal for firing large boiler units at high combustion rates, has resulted in furnace temperatures which make it highly desirable that the refractory furnace wall surfaces be protected by some form of water-cooled surface. This also holds true to a lesser extent in the case of stoker-fired boilers. A number of different types of water screens have been proposed for the purpose of protecting the furnace walls of the various types of furnaces.

In order properly to perform their function as a protecting means, such screens should present to the combustion gases as nearly an unbroken water-cooled surface as possible, and in the screens heretofore proposed, which take the form of a plurality of parallel tubes joined by inlet and outlet headers, the close spacing of the tubes desired has been obtainable only by staggering the tube ends, because of the distance necessary between the tube holes in the header, in order to insure sufficient ligament strength in the latter. This construction is undesirable, as it necessitates the use either of headers of very large sectional area, or of double headers. Moreover, because of the severe temperature conditions to which such screens are subjected, it is desirable that the minimum number of joints be used in the screen structure.

In some cases the joints within the setting may be eliminated by carrying the individual screen tubes through the furnace walls to outside headers, but in order to reduce the possibility of air leakage incurred by a large number of tubes passing thru the walls at a point where expansion stresses are severe, it is generally most desirable to place both tubes and headers within the setting.

It is the object of my invention, therefore, to provide a water screen which will present a substantially unbroken water-cooled surface, composed of a plurality of integral tubular units which may be connected as desired into any form of boiler and the end

portions of which may be in spaced relation in a single plane when the tubular portions of such units are substantially contacting. A further object of the invention is the provision of a screen structure composed of a plurality of tubular units, connected into headers or equivalent elements, in which the number of joints between the tubes and the elements to which they may be connected is reduced to a number such that the total number of joints necessary does not exceed the number of tubes used. A still further object of the invention is the provision of a water screen structure which is capable of withstanding the extreme temperature conditions existing in a boiler furnace and which may be placed entirely therein, so that the number of connections extending through the furnace walls may be reduced to a minimum; that is, limited to the inlet and outlet connections, or, if desired, connected into the circulating system wholly within the setting. Other and more detailed objects of the invention will appear in connection with the following description of an illustrative embodiment of the invention as applied to a boiler of the general type disclosed in my copending application, Serial No. 747,032, filed October 31st, 1924.

In the accompanying drawings, Fig. 1 is a central vertical longitudinal section taken through a boiler of this type mounted in a setting adapted for firing by fuel oil, and Fig. 2 is a section taken on the line 2—2 of Fig. 1.

Referring now to Fig. 1, the boiler illustrated resembles the conventional form of cross-drum water tube boiler and comprises the main steam and water drum 1 and a bank of horizontally inclined steam-generating tubes 2, arranged in two triangularly shaped banks over a central combustion chamber, the latter having an A-shaped roof formed by the tube banks, as is more clearly shown in Fig. 2. At their upper ends the generating tubes 2 are connected into vertical upflow headers 3, the lower ends of which are placed at progressively higher levels as the longitudinal center line of the boiler is approached. The headers 3 are connected by nipples 4 to a common transverse header 5, which is in turn connected to the steam and water drum 1 by the circulators 6. The lower ends of the generating tubes 2 are connected into a series of verti-

90

95

100

110

cal downflow headers 7, similar in arrangement to the headers 3, the headers 7 being supplied with water from drum 1 by means of nipples 8.

- 5 The roof of the boiler is formed by a series of tiles 9 supported on the upper rows of tubes and sloping upwardly from each side of the longitudinal centre line of the boiler. At both sides of the boiler the upper rows
- 10 of generating tubes 2 are replaced by a series of economizer tubes 10, connected into upper and lower header boxes 11 and 12 and delivering heated feed water to the drum 1 through pipe 13.
- 15 The sets of nipples 4 and 8 are increased in refractory tile to form gastight walls above the level of the headers 3 and 7, and refractory side walls are provided which terminate at their upper ends at a point
- 20 below the level of the roof tiles 9. An outer casing 15 is provided which extends, upwardly to the top of the boiler and terminates in the breeching 16. The side walls of the outer casing 15, extending upwardly
- 25 beyond the inner walls 13 and 14, provide passage-ways 17 and 18, extending the full longitudinal length of the boiler (see Fig. 2) connecting the steam generating and economizer banks with the breeching for the exit
- 30 of the combustion gases.

It is to be understood, however, that the present invention which is concerned with the protection of the furnace and combustion chamber walls, is not to be limited to application with this form of boiler, but may be equally well applied to any desired form.

In the furnace chosen for illustration, oil burners 19 and 20 are provided in the front 40 and rear furnace walls respectively, and the side walls 13 and 14 of the furnace are each protected above the level of the burners by a water screen embodying the present invention. The side wall screens are each composed of a number of integral tubular units, each of which is formed by a plurality of tubes 21, which at their ends are merged into a single tubular end portion 22, having a cross-sectional area substantially equal to 45 that of all the tubes in the unit and a diameter substantially smaller than the width of the unit intermediate the end portions. The circular end portions 22 of the units which join the circular pipe portions may 50 be formed integrally by the forging process described in Patent No. 1,155,110, issued to C. H. True and N. T. McKee and the end of the portion 22 brought down to the desired diameter by the process described in 55 Patent No. 1,255,355 issued to C. H. True and C. A. Brandt. The units are formed with the tubes 21 in substantially contacting relation and the screen is formed by a plurality of units placed in close juxtaposition, so that a substantially unbroken water

wall is provided, lining and protecting the inner faces of the refractory side walls 13 and 14. The units are placed in a horizontally inclined position corresponding to the inclination of the generating tubes 2 and are connected at their upper ends into vertical headers 23, which discharge into the main drum 1 through the risers 24 extending upwardly outside the boiler casing. At their lower ends the units are connected into vertical headers 25 corresponding to the upper headers 23, and water is supplied through the downflow pipes 26, which are connected into headers 25 at points 26^a and 26^b.

In the embodiment shown, due to the use of oil burners, the boiler setting is comparatively low, which results in the furnace side walls being greater in length than in height. For this reason the units forming the water screen are placed longitudinally, as in this position the screen may be formed of a comparatively small number of long units, which is desirable because of the small number of joints required. It will be obvious, however, that this particular disposition of the side wall units need not be adhered to and that they may be placed at any desired angle to the horizontal. The most desirable disposition of the units is that which requires the minimum number of units for the protection of a given wall area and in the case of a pulverized fuel installation, having a high and comparatively narrow furnace, this condition would best be met by placing the units vertically rather than in a horizontal or inclined position.

The front wall 27 of the boiler setting, below the level of the headers 3, is protected by a screen formed of units similar to those employed in the construction of the side wall screens. The front wall units are formed of tubes 28 joined at their ends to form single integral end portions 29, and in this instance the units are placed vertically in closely spaced relation with their lower ends entering a common transverse header 30 and their upper ends entering the lower ends of the corresponding upflow headers 3, into which they discharge. Water is supplied to the front wall screen by means of the pipes 31, which connect into the downflow pipes 26, supplying the side wall screens.

As shown in Fig. 2, header 30 is provided with hand hole openings and covers 30^a opposite the unit ends 29, for the purpose of inserting cleaning tools into the units, and the headers 23 and 25 of the side wall screens are similarly equipped. Inasmuch as the screen tubes have a very high evaporative rate, the tendency to form scale therein is 125 pronounced, and because of the severe temperatures to which they are subjected it is imperative that they may be readily cleaned of scale accumulations. In this connection it is particularly to be noted that the form 130

of the unit end portions 22 and 29 permits the easy insertion of a cleaning tool into any of the tubes in the unit.

The rear wall of the furnace proper is built up of refractory material 32 and the rear wall between the furnace setting and the headers 7 is formed and made gas-tight by means of nipples 33 extending from the bottom of the headers 7 to a common transverse header 34, and which are encased in refractory packing 35.

It will be readily apparent from the preceding description that I have provided by my invention a form of water screen in which the maximum amount of screening surface may be obtained in the form best adapted to withstand high pressures—that is, tubular—and with the minimum number of joints exposed to the high temperatures of the boiler furnace. It will further be apparent that by my invention, I am able to place water screen tubes in substantially contacting arrangement and at the same time provide sufficient space between the tube holes required in the headers to insure a sufficient ligament strength in the latter. While in the present embodiment I have shown the tubular portion of the units arranged in a single plane parallel to the wall surface, it will be obvious that the individual units may be turned about their longitudinal axes to any degree desired, so that either a row of staggered tubes or a double row of tubes may be interposed between the furnace wall and the combustion chamber. It will further be obvious that the number of individual tubes per unit need not be limited to two but may be increased by the process described in Patent No. 1,264,455 issued to C. H. True, as, for example, to groups of three which may be arranged in alined relation, or, in case it is desired to provide more cooling surface between the wall and the combustion chamber than can be provided with a single row of tubes, may be arranged in triangular relation.

It is further to be understood that while I have described a particular arrangement of water screen adapted to a particular boiler, the invention is not to be limited by the location of the screen nor the manner in which it is connected into the boiler system, as it is readily applicable to substantially all forms of combustion chambers and, moreover, need not be connected into the boiler circulating system in case it is desired to supply it with water from some other source.

I claim:

1. A water screen comprising a plurality of water tubes circular in cross section and arranged in closely spaced parallel relation to form a substantially unbroken water wall, said tubes being divided into groups with the tubes of each group integrally joined at

their ends to form units having single tubular end portions, the width of the tube group of each unit being greater than the diameter of either end portion of the unit and the internal cross-sectional area of each end portion being not less than the total internal cross-sectional area of the corresponding tube group, and means forming part of a water circulating system to which the end portions of said units are connected.

2. A water screen comprising a plurality of water tubes circular in cross-section and arranged in closely spaced parallel relation to form a substantially unbroken water wall, said tubes being divided into groups of two tubes each with the tubes of each group integrally joined at their ends to form units having single tubular end portions, the width of the tube group of each unit being greater than the diameter of either end portion of the unit, and the internal cross-sectional area of each end portion being not less than the total internal cross-sectional area of the corresponding tube group, and means forming part of a water circulating system to which the end portions of said units are connected.

3. A water screen comprising a plurality of water tubes circular in cross-section and arranged in the same plane in closely spaced parallel relation to form a substantially unbroken water wall, said tubes being divided into groups with the tubes of each group integrally joined at their ends to form units having single tubular end portions, the width of the tube group of each unit being greater than the diameter of either end portion of the unit and the internal cross-sectional area of each end portion being not less than the total internal cross-sectional area of the corresponding tube group, and means forming part of a water circulating system to which the end portions of said units are connected.

4. A water screen comprising a plurality of water tubes circular in cross-section and arranged in the same plane in closely spaced parallel relation to form a substantially unbroken water wall, said tubes being divided into groups of two tubes each with the tubes of each group integrally joined at their ends to form units having single tubular end portions, the width of the tube group of each unit being greater than the diameter of either end portion of the unit and the internal cross-sectional area of each end portion being not less than the total internal cross-sectional area of the corresponding tube group, and means forming part of a water circulating system to which the end portions of said units are connected.

5. A water screen comprising a plurality of water tubes circular in cross-section and arranged in closely spaced parallel relation to form a substantially unbroken water wall, said tubes being divided into groups with

- the tubes of each group integrally joined at their ends to form units having single tubular end portions, the width of the tube group of each unit being greater than the diameter of either end portion of the unit and the internal cross sectional area of each end portion being not less than the total internal cross-sectional area of the corresponding tube group, and headers forming part 10 of a water circulating system to which the end portions of said units are connected.
6. A water screen comprising a plurality of vertical water tubes circular in cross section and arranged in closely spaced parallel relation to form a substantially unbroken water wall, said tubes being divided into groups with the tubes of each group integrally joined at their ends to form units having single tubular end portions, the 15 width of the tube group of each unit being greater than the diameter of either end portion of the unit and the internal cross sectional area of each end portion being not less than the total internal cross-sectional area of the corresponding tube group, and means forming part 20 of a water circulating system to which the end portions of said units are connected.
7. A water screen comprising a plurality of water tubes circular in cross-section and arranged in closely spaced parallel relation to form a substantially unbroken water wall, said tubes being divided into groups of two tubes each with the tubes of each group integrally joined at their ends to form units having single tubular end portions, the width of the tube group of each unit being greater than the diameter of either end portion of the unit, and the internal cross-sectional area of each end portion being substantially greater than the internal cross-section 30 area of each end portion intaking from the water circulating system being substantially greater than half the internal cross-sectional area of the tubes associated therewith.
8. A water screen comprising a plurality of water tubes circular in cross-section and arranged in closely spaced parallel relation to form a substantially unbroken water wall, said tubes being divided into groups with the tubes of each group integrally joined at their ends to form units having single tubular end portions, the width of the tube group of each unit being greater than the diameter of either end portion of the unit, and the internal cross-sectional area of each end portion being substantially greater than half the internal cross-sectional area of the tubes associated therewith. 35
9. A water screen comprising a plurality of water tubes circular in cross-section and arranged in closely spaced parallel relation to form a substantially unbroken water wall, said tubes being divided into groups with the tubes of each group integrally joined at their ends to form units having single tubular end portions, the width of the tube group of each unit being greater than the diameter of either end portion of the unit, means forming part of a water circulating system to which the end portions of said units are connected, the internal cross-sectional area of each end portion intaking from the water circulating system being substantially greater than half the internal cross-sectional area of the tubes associated therewith. 40
